UNITED STATES PATENT OFFICE.

OTTO S. BEYER, OF BROOKLYN, NEW YORK, ASSIGNOR, BY MESNE ASSIGNMENTS, TO
E. W. BLISS COMPANY, OF BROOKLYN, NEW YORK, A CORPORATION OF DELAWARE.

RADIATOR.

Application filed August 7, 1924. Serial No. 730,632.

This invention relates to improvements in radiators and more especially light gauge metal radiators, and aims to provide improvements therein.

5 In the construction of these light gauge metal radiators, sheet metal has commonly been used, one or more pieces of the sheet metal being used to form a section. Seams of considerable length are required to unite 10 the meeting edges of the sheet or sheets of metal forming each section, and the production of an enduring leak-tight seam has been either unsatisfactory or costly.

The present invention provides a radiator 15 simulating the shape and form of the usual house-heating radiator, which, being formed of drawn or extruded shells, or of tubes with an end or end seams, or a seam running transversely thereof, and which in thin 20 gauge metal and without long straight or substantially straight seams, avoids the objection to seams encountered in radiators formed of light gauge sheet metal.

The invention further provides a novel 25 method of forming the radiators.

A number of embodiments of the invention are illustrated in the accompanying drawings, in which—

Fig. 1 is a side elevation of a radiator according to the first embodiment of the invention, with parts shown in section.

Fig. 2 is an end elevation of the radiator shown in Fig. 1.

Fig. 3 is an enlarged cross-section on the line 3—3 of Fig. 2.

Fig. 4 is a view, in elevation, of a shell from which the sections of the radiator are formed.

Fig. 5 is a view, similar to Fig. 1, of a 40 second embodiment of the invention.

Figs. 6 and 7 are elevational views of one of the sections, Fig. 7 showing the section at right angles to the view Fig. 6.

Figs. 8 and 9 are views of shells, showing 45 intermediate steps in the formation of the sections.

Fig. 10 shows another embodiment of the inventive idea, being a vertical sectional view.

50 Referring to said drawings, and first more especially to Figs. 1 to 4, inclusive, numeral 10 designates the radiator comprising a plurality of sections 11, each of which is a drawn or extruded shell of the character of

the shell 13 illustrated in Fig. 4 of the 55 drawing. The shells constituting the sections 11 are preferably flattened as indicated at 15, a round shell such as 13 being first formed and then flattened.

The sections 11 are preferably assembled 60 in such manner that the flat faces of adjoining sections face one another.

The plurality of sections 11 are connected for intercommunication, and also for rigidity, at top or bottom, and preferably at both 65 top and bottom, as indicated at 20, 21.

The connecting means 20, 21 are conveniently short tubes or nipples 23, 24, oppositely threaded, and fitting openings 27, 28 in the sections 11. 70

As the walls of the sections 11 may be, and preferably are, of a light gauge, having a thickness corresponding to about 20, B. & S. gauge or lighter, for example, the openings 27, 28 are conveniently bushed or rimmed 75 with rings 30, which are seamed or crimped upon the edges of the metal around said openings 27, 28, and threads are provided in these rings 30 for engaging the threads on the nipples 23, 24. 80

The sections 11 are preferably embossed adjacent the openings 27, 28, as indicated at 33, to stiffen the sections at these points, and also to provide space between the nipples corresponding to the thickness of the 85 sections.

The sections 11 are also preferably corrugated lengthwise, as indicated at 35, Figs. 2 and 3. These corrugations serve to strengthen the sections, and also provide 90 constrictions 37 lengthwise of the sections, forming channels 38 between the constrictions, to facilitate the flow or circulation of the heating fluid.

The open end 40 of the tube is closed in 95 suitable manner. The end is preferably flattened so that the edge portions lie together, and the length of the edges being short it is neither difficult nor expensive to close the ends by practically any usual means. The 100 preferred means is a strip of relatively heavy metal 42 (Figs. 1 and 2), which is seamed or crimped on the end 40. Such a joint will be durable, and not affected by

strains, shocks, etc., to which the radiator 105 may be subjected, to the same extent as long seams, as for example those in sheet metal radiators.

Referring now particularly to Figs. 5 to 9, inclusive, of the drawings, the numeral 50 designates the radiator comprising a plurality of sections 51, each of which is a drawn or extruded shell of the character of the shell 13 shown in Figs. 9 and 4 of the drawing. The shells constituting the sections 51 are preferably flattened, as indicated at 55.

10 The sections 51, like the sections 11, are preferably assembled in such manner that the flat faces of adjoining sections face one another.

15 The plurality of sections 51 are connected for intercommunication, at top or bottom, being here shown as connected to a base or manifold 57, and as being in communication with one another through the manifold and the open end of each shell or section, as indicated at 59.

20 The open ends of the sections or shells 51 may be connected to the base or manifold 57 in any suitable manner. Preferably the open ends of the shells have a neck 60 of reduced diameter, which neck has a flange 62 thereon, adapted to be pressed against a neck 64 formed upon the base or manifold 57. The flange 62 is conveniently pressed against said neck 64 by a coupling or collar 66 having threaded connection with said neck 64, as indicated at 68. The manifold or base 57 is formed with a plurality of these threaded necks 64 to provide for the connection of the several sections making up the radiator. The means of connection described provide a convenient means for connecting the sections to the base where the space between the sections is less than the width of the section. Any other means of connecting the sections to the base or manifold may be used which is suitable to any particular arrangement of the sections with relation to the manifold, which may be chosen.

45 The sections are also preferably connected for rigidity, as for example, by means of a strap or straps 70, 71, passing around the series of sections, as illustrated in Fig. 5.

50 Where the walls of the sections 55 are of light gauge metal, having a thickness corresponding to about 20, B. & S. gauge, for example, the flange 62 is a practical means for uniting the sections to the base or manifold.

55 The sections 55 are preferably corrugated lengthwise, as indicated at 75, Fig. 6, similarly to the corrugations 35, Fig. 2. These corrugations serve to strengthen the sections and also provide constrictions lengthwise 60 of the sections, forming channels between the constrictions to facilitate the flow or circulation of the heating fluid, as described in reference to the embodiment illustrated in Figs. 1 to 3, inclusive.

65 The sections 15 or 51, shown in Figs. 1

and 5, may be formed of two light gauge shells 76, 77 Fig. 10, joined together suitably at their open ends, as by a seam 78.

Method.—According to the present method, the sections or shells 11 and 51 are formed by drawing or extruding deep shells 13 open at one end, as indicated at 40, Figs. 4 and 9. These shells are then flattened as indicated in Figs. 3 and 7 of the drawing.

The flattened shells are then preferably 75 corrugated or indented longitudinally, as indicated at 35 and 75, Figs. 2 and 6, the indentations or corrugations forming constrictions 37, between which constrictions 37 channels 38 are provided for the circulation of the heating fluid.

The walls of the tube 13 are drawn quite thin, as for example to a thickness of No. 20 B. & S. gauge or less.

25 A plurality of shells or sections are assembled into the form of a radiator, the interiors of the sections being in communication, as indicated in Figs. 1 and 5 of the drawings.

30 According to one specific procedure, the 90 margins of the shell at the open end are pressed together, and closed in suitable manner, as by means of a strip of metal 42 which is crimped or seamed upon the edges of the section. Openings 27, 28 may be formed 95 in the upper or lower portions of the shell, or in the upper and lower portions of the shells, and one shell or section joined to another by a nipple or nipples threaded in said opening or openings.

35 According to another specific mode of procedure, the open end 40 of the shell 13 may be reduced to form a neck 60, as indicated in Fig. 8. A flange 62 is preferably formed at the outer end of the neck 60.

40 The sections with the necks 60 may be joined together to form a radiator, by connecting the sections through the necks 60 with a suitable base or manifold 57, Fig. 5. A threaded coupling or flanged collar 66 110 serves to clamp the flange 62 against a part of the base or manifold 57.

45 The inventive ideas may receive other embodiments than those herein specifically illustrated and described, and the method 115 may be carried out by other modes of procedure than those specifically described.

What is claimed is:

1. A metal radiator comprising sections composed of longitudinally-flattened shells of light gauge closed at one end, said shells being seamless throughout.

2. A metal radiator comprising longitudinally flattened shells of light gauge, said shells being closed at one end and seamless throughout, said flattened sides being constricted longitudinally for providing channels for circulation.

3. A metal radiator comprising longitudinally-flattened shells of light gauge, said

shells each being closed at one end and seamless throughout, and having a neck of reduced diameter provided with a clamping flange at its open end. together as not to be able to be turned, said shells having reduced necks, a base or manifold, and couplings on said necks connecting said shells to said manifold.

5. 4. A metal radiator comprising longitudinally seamless shells of light gauge, said shells being flattened and arranged so close

In witness whereof, I have hereunto signed my name.

OTTO S. BEYER.
